UNITED STATES PATENT OFFICE.

GEORGE W. MOSHER, OF NEWPORT, KENTUCKY.

MAIL-POUCH-EXCHANGING DEVICE.

No. 823,617.

Specification of Letters Patent.

Patented June 19, 1906.

Application filed December 20, 1905. Serial No. 292,590.

To all whom it may concern:

Be it known that I, GEORGE W. MOSHER, a citizen of the United States, residing at Newport, in the county of Campbell and State of Kentucky, have invented new and useful Improvements in Mail-Pouch-Exchanging Devices, of which the following is a specification.

My invention relates to mechanism for 10 catching and delivering mail-pouches, part of which apparatus is attached to and travels with the mail-car and another part stationary and in convenient proximity to the track upon which the said car travels.

Both the stationary and traveling parts 15 are provided with means for holding for delivery a mail-pouch which is to be caught by the other, and both are provided with means for catching a pouch so held for delivery by 20 the other. All this mechanism is so constructed that either part can both deliver and catch at approximately the same time or either can catch when there is nothing to deliver or deliver when there is nothing to 25 catch.

My device may be readily changed from one 30 side of the car to the other without any alteration of the mechanism itself, and it may be pushed aside from the door entirely out of the way when loading and unloading car, so 35 special small car-doors where mail-catcher is used may be dispensed with. It does not require the constant attention of a mail clerk, as bag to be delivered from car may be placed and device set and left. This insures lessening 40 of labor and eliminates the danger to attending mail clerk of being struck by the pouch as it is caught.

As the pouches will not be kicked from 45 moving cars, but retained on a suitable delivery device, mail-matter will not be damaged by pouch accidentally striking objects violently in falling, nor moisture, as at present when pouch happens to fall into mud-puddles and the like in wet weather.

With the device now in use in the United 50 States three or four per cent. of the pouches hung out to be caught by passing trains are missed, and these are frequently knocked down and must lie there until picked up by local attendant. My device avoids the necessity of trusting entirely either to the dexterity or attentiveness of the mail clerk entrusted with the work of catching and delivering pouches.

When it is considered that his work requires great skill and steadiness, and that with the device now in use the appropriate action must be forthcoming at the exact instant required in order to secure proper delivery and receipt of pouches, the importance of this advantage will appear.

My invention is illustrated in the accompanying drawings, in which—

Figure 1 is a front elevation of the stationary portion of my mechanism complete with pouch caught in jaw. Fig. 2 is a side elevation of a mail-car with ends broken away and with the moving portion of my mechanism complete empty and pushed aside out of the way for loading and unloading at a full-stop point. Fig. 3 is a side elevation of the stationary portion of my device with its pouch fixed ready to be caught and a vertical section through a mail-car, parts broken away, showing the traveling portion of my device with its pouch fixed ready to be caught, all showing stationary and traveling portions of my device about to contact for operation. Fig. 4 is the same just after the exchange of pouches has been made. Fig. 5 is a top plan view of the catching-arm and attendant parts of the stationary device. Fig. 6 is an under plan view of the catching-arm and attendant parts of the portion of the mechanism attached to the car. Figs. 7 and 8 are hinges for the car catching and delivering mechanism when same is made so as to be quickly changed from one side of the car to the other. Fig. 9 is a side elevation of the stationary portion of the device set to receive when there is no pouch to deliver and shows trip-lever with pawl. Fig. 10 is a detail of the trip-lever with pawl.

The frame for the stationary portion of my invention (represented as a whole by B) consists, preferably, of two upright posts *b*, suitably set in the ground and connected by one or more pieces *b'*, or in any other convenient manner, to form a rigid support for the stationary pouch delivering and catching device, (designated as a whole by A,) attached to frame B by hinges *a* to permit A to swing up and down. This catching-arm may be formed of any number of suitably-shaped parts, and the preferred form shown has the main frame *a'*, with sloping jaws *a²* and *a³* on each end, adapted to guide the pouch into the further narrowed recess *a⁴*. The outer sloping jaws are prolonged and terminate in

projections a^5 , extending outwardly laterally and adapted to engage and hold a mail-pouch ring, as shown in Fig. 3. The back portion of the part a' may be extended laterally, forming projections a^6 , to which levers b^3 are attached in any convenient manner, as by eyelet, and held by cotter-pin a^7 . These levers extend upward and are pivotally attached to levers b^4 , near the back end thereof. At their outer end levers b^4 are each provided with a projection b^5 . These extend divergently laterally and are adapted to engage and hold the other mail-pouch ring, as shown in Fig. 3. Levers b^4 are each pivoted in a bracket b^2 , which is attached to post b and extends outwardly toward the track. The main frame has attached to it by pivot a^9 , or in any other suitable manner at any convenient point, a latch a^8 , adapted to be pressed back to admit the mail-pouch as it enters the jaw and to drop into position and retain it within the recess a^4 , the face a^{10} completing the inclosure. This face may be serrated or roughened to more securely hold the pouch and to catch on the folds of the pouch as it is being rotated to remove it from the catch.

Springs a^{11} a^{11} , attached to the latch at suitable points on the main frame, hold the latch normally closed, as shown in Fig. 5, but permit the latch to turn freely on its pivot a^9 , as when mail-bags are admitted or removed. On the under side of the frame a' is a lug a^{20} , adapted to contact with a suitable projection b^8 on the pawl-lever b^7 . At a convenient point, as under the main frame a' , is attached a spring a^{12} , while the other end is made fast to the frame B. This serves to hold the part A downward to hold the mail-pouch taut. A bent lever b^7 , attached to some convenient part of the frame B, as a cross-bar b^6 , by staple, or in any other convenient manner, is provided near its bend with a projection b^8 , which is adapted to contact with lug a^{20} to sustain the weight of the part A when there is no pouch to be delivered to the car and one is to be taken from the car mechanism. This lever then projects outwardly beyond the bend, so as to contact with the pouch when it is carried into the recess a^4 . The impact of the pouch forces the outer end b^9 of lever over, projection b^8 is carried out of holding contact with lug a^{20} , and both lever and part A fall and hang in an approximately vertical position. The end b^9 of the lever b^7 is broadened, so as to insure its extending into the path of the pouch as it enters recess a^4 .

While the device shown is double, to permit its use for exchanging mail-pouches while train is passing in either direction, it is obvious that it may be made single only, if desired.

The traveling portion of my device consists of a swinging member C, similar in many respects to the member A of the stationary part of the device, the main frame c' corre-

sponding to a' , except that there are no projections corresponding to a^6 nor projections corresponding to a^5 ; but the frame C is terminated outwardly with three prongs, to the middle one of which, c^{13} , is secured a spring c^{14} , which extends to the side prongs and is so shaped at these ends as to hold the ring of a pouch securely at the points c^{15} c^{16} , but still yieldingly, so that the impact of the car-pouch with the stationary catch will drag the pouch-ring off the catch c^{15} . Parts on A and C (marked with same index-numerals) are similar and further description would be but repetition.

Preferably on the back side of the main frame is a handle c^{18} of convenient length and size so that the mail clerk may by pressing down upon it raise the whole device C to effect the exchange of mail pouches. The parts of the mechanism permanently fastened to the car are designated as a whole by D. The horizontal bar d is rigidly fastened to the car on either side of the doorway in any convenient manner, as by door-plates d^2 . On this bar the car exchange mechanism C is hung, so that it may be slid readily to any part of the opening or out of the way of the opening altogether, as shown in Fig. 2. If the exchange mechanism is to be made quickly detachable, instead of providing fingers c with eyelets I form them with recesses c^{17} , into which the rod d fits. Plate c^{18} fits over the open sides of these slots and is fastened into place in any convenient manner, as by a screw through hole c^{19} , threaded into handle c^{16} and main frame c' .

Hooks d' , fastened to any convenient adjoining point, as the inner side of car-door, are adapted to receive and hold the handle c^{18} , so that exchange mechanism C may be maintained in any approximately horizontal position without the constant effort and attention of the operator. These hooks may be used or not, at the option of the operator.

On each side of the doorway is an arm d^3 with hook d^4 , projecting laterally toward the door and adapted to receive and sustain a mail-pouch ring. These arms are normally held against the side of the car by springs d^5 or in any other suitable manner. When pouches are to be delivered only by either part of device, the same preparation is made as where they are to be exchanged, for the catching mechanism of each is always ready for use when the delivery mechanism is "set." When pouches are to be received only on the car mechanism, the arms d^3 are not raised, the mechanism C being raised, as before described. When pouches are to be received only on the stationary mechanism, the preparation is as previously described, but there being no pouch to hold the mechanism in position, a pawl b^6 is attached to some convenient point on the frame under the mechanism A, a notch (not shown) provided in the

under part of A and adapted to contact with the free end of said pawl to sustain A, while in such horizontal position, for catching.

The operation is as follows: That stationary exchange mechanism A is lifted up against the force of the springs a^{12} to an approximately horizontal position and through connecting-levers b^3 b^3 levers b^4 b^4 are depressed to an approximately horizontal position. A mail-pouch is then hung on the side away from that on which the train approaches with which an exchange of pouches is to be effected by hooking one ring of said pouch into a hook b^5 and the other into a corresponding hook a^5 . The pouch is thus held taut and ready to be caught by the catching mechanism carried by the train. The catching mechanism of both parts of the device is always ready for use. When nearing a point where pouches are to be exchanged without stop, the moving exchange mechanism C is slid opposite the door, a pouch-ring placed in the hook c^{15} toward the rear end of the car and the other ring placed in the hook d^4 toward the front end of the car, and the operator bears down on handle c^{16} until the mechanism C is brought to an approximately horizontal position, when the handle c^{16} may be placed in the hook d^4 next the front end of the car. When pouches at the station and on the car have been so arranged and the passing train arrives at the stationary device, the mechanisms are of such a height that the middle of the pouch on the car mechanism contacts with the slanting face of the catch a^8 , which catch turns on its pivot, allows the pouch to enter the recess a^4 , when a spring a^{11} quickly throws the latch back to position and holds the pouch securely in the jaw, and in the meantime the pouch has been removed from hooks c^{15} and d^4 , and immediately thereafter, the same action takes place with the pouch to be taken from the stationary mechanism by the car mechanism, removing that pouch from the hooks a^5 b^5 .

I claim as my invention and desire to secure by Letters Patent of the United States—

1. In a mail-pouch-exchanging device, the combination of a fixed frame suitably placed in proximity to a railway-track said frame carrying a combined pouch delivering and catching mechanism, said catching mechanism comprising a forked member and a latch guarding the entrance thereto, said latch adapted to be pressed aside by an entering pouch, and a spring adapted to return said latch to position, and a combined pouch holding and catching mechanism attached to a mail-car.

2. In a mail-pouch-exchanging device, the combination of a fixed frame suitably placed in proximity to a railway-track, said frame

carrying a double pouch holding and catching mechanism, said catching mechanism provided with a latch adapted to be pressed aside by an entering pouch and a spring adapted to return said latch to position and a combined double pouch holding and catching mechanism attached to a mail-car, said car mechanism also provided with said latch and spring.

3. In a mail-pouch-exchanging device the combination of a frame fixed in proximity to a railway-track, a mail pouch receiving and delivering mechanism attached to said frame and including a plate having its opposite ends forked, and a spring-pressed latch controlling the entrance to each of the forks of said plate, a substantially corresponding pouch holding and catching mechanism attached to a car, and a mechanism on the car upon which the pouch holding and catching devices of said car are movably supported.

4. In combination with a mail-pouch-exchanging device, a combined receiving and delivering car mechanism said mechanism including a member having its opposite ends forked, a spring-latch guarding the entrances to said forks, means whereby the forked plate is hung from the car, a handle whereby said plate may be turned about its support, and means adapted to engage and hold said handle to maintain the plate in position.

5. In combination with a mail-pouch-exchanging device, a combined receiving and delivering car mechanism, and readily-removable means for slidably hinging said mechanism on a horizontal bar across the car-door, said means including said bar, guides having recesses for the bar, plates fitting over the open sides of the recesses and means for securing said plates.

6. A mail-pouch-exchanging device, consisting of a fixed frame suitably placed in proximity to a railway-track, a double pouch holding and catching mechanism horizontally hinged thereto, said catching mechanism consisting of a bifurcated plate, the entrance to which is guarded by a latch yieldably held in position by springs; and a combined double pouch holding and catching mechanism similar to the one above mentioned so attached to a horizontal bar across the side doorway of a railway mail-car as to be readily removable therefrom or to be slid on said bar clear of the doorway.

In testimony whereof I have hereunto set my hand in presence of two subscribing witnesses.

GEORGE W. MOSHER.
